CLAIM

The ornamental design for a table, as shown and described.

DESCRIPTION

FIG. 1 is a front perspective view of a table showing our new design;

FIG. 2 is a side elevational view thereof;

FIG. 3 is a front elevational view thereof, the rear elevational view being a mirror image;

FIG. 4 is a top view thereof; and,

FIG. 5 is a top view of a second embodiment of our new design, the side and front elevational views being identical to FIGS. 2 and 3; the front perspective view of the second embodiment being similar to FIG. 1 but with the top as shown in FIG. 5.
